COMBINED CONTAINER AND CLOSURE THEREFOR

Milton Immermann, Piermont, Archie G. Drummond, Jr., Wantagh, and Harold J. Vanderhyde, North Merrick, N.Y., Robert C. Fogle, Darien, Conn., and Roger H. Sweet, Bayside, and Calvin Lee Payne, Jr., Hastings on Hudson, N.Y., assignors to Clayton Anderson & Co., Dallas, Tex., a corporation of Delaware

Filed Sept. 24, 1965, Ser. No. 87,156

Term of patent 14 years

(Cl. D58—12)

FIGURE 1 is a perspective view of a combined container and closure therefor embodying our new design; FIGURE 2 is a top plan view thereof;

FIGURE 3 is a side elevational view thereof, the opposite side being the same;

FIGURE 4 is an end elevational view thereof, the opposite end being the same;

FIGURE 5 is a bottom view thereof; and

FIGURE 6 is a fragmentary sectional view, to an enlarged scale, taken along line 6—6 of FIGURE 2.

We claim:

The ornamental design for a combined container and closure therefor, as shown and described.
